INVENTOR

UNITED STATES PATENT OFFICE.

WILLIAM J. GILMORE, OF NEW YORK, N. Y.

DESIGN FOR A PEN-RACK.

SPECIFICATION forming part of Design No. 22,861, dated October 31, 1893.

Application filed September 23, 1893. Serial No. 486,829. Term of patent 3½ years.

To all whom it may concern:

Be it known that I, WILLIAM J. GILMORE, of the city of New York, in the county of New York and State of New York, have invented and produced a new and original Design for a Pen-Rack; and I do hereby declare the following to be a full, clear, and exact description of said invention, reference being had to the accompanying drawing, and to the letters of reference marked thereon, which form a part of this specification.

My invention is a new and original shape or configuration of a pen rack.

The pen-rack is made in the form shown in the figure of the drawing herewith, consisting of a square or oblong shape, with shelves projecting from the front, and inclined at a sharp

angle so as to make a depression in which the pen rests. It is supported in an inclined position by a projection from the rear part shown at A. This base is scalloped on the edge as shown. The shelves are shown at B, and are continuous from one side to the other. The top of the pen-rack is in form of an arch, as shown in the drawing.

What I claim is—

The design for a pen-rack substantially as shown and described.

In testimony whereof I affix my signature in presence of two subscribing witnesses.

W. J. GILMORE.

Witnesses:

JOHN HENRY HULL,
FRANK S. OBER.
